MACHINE FOR RECLAIMING YARN FROM
KNITTED FABRICHans Westkott, West Reading, Pa., assignor to
Berkshire Knitting Mills, Wyomissing, Pa., a
corporation of Pennsylvania

Application January 11, 1933, Serial No. 651,114

9 Claims. (Cl. 28—17)

This invention relates to a machine for reclaiming thread from imperfect knitted fabric, by pulling the thread in a manner to unravel the successively formed courses of stitches of which the fabric is composed; and by winding the thread upon a suitable spool, bobbin, reel, core, or other package-forming element for use in reknitting or other desirable purposes.

The present invention relates more particularly to mechanism for releasing the thread-pulling element from the mechanism by which it is operated to pull the thread. The thread-pulling element in the present instance constitutes the core element upon which the thread is wound.

One object of the invention is to provide sensitive and effective releasing mechanism for the core element, whereby rotation of the core element in a direction to wind the thread thereon will be immediately arrested when the tension on the thread, intermediate the core element and the fabric being unraveled, attains a predetermined value, less than the tensile strength of the thread.

Another object of the invention is to provide means whereby the amount of release resistance may be varied in accordance with the tensile strength of the thread of the fabric that is to be unraveled.

The machine chosen for the purpose of illustrating the present invention is of the type including a friction drive for the core element, which comprises a constantly rotating friction element and a cooperating releasable friction element, which latter is operatively connected to the core element upon which the thread is to be wound.

In machines of this type, according to the prior art, when the tension on the thread attains a predetermined value the rotary winding motion of the core element is automatically interrupted. Release of the core element from the constantly rotating drive element permits the core element to rotate reversely, under the tension built up in the thread, whereby a portion of the thread unwinds from the core element, which effects slackening of the tension in the thread, intermediate the core element and the fabric being unraveled. Slackening of the thread automatically permits the reestablishment of the friction drive, whereby the core element is again rotated in a direction to wind the thread thereon. Such alternate release and application of the drive effects an intermittent jerking of the thread, which, if continued, causes

the thread to be broken, the loose end of the thread in some instances becoming entangled in the moving elements of the machine.

Another object of the invention is to provide means whereby the core-rotating means is held in complete ineffective relation to the constantly rotating element of the friction drive, from the moment of its release therefrom until the cause of the excessive resistance confronting the unraveling of the thread from the fabric has been removed, whereby intermittent jerking of the thread is effectively prevented.

Another object of the invention is to provide a brake for the core element which will become effective simultaneously with the release of the core element from the constantly rotating element of the friction drive, whereby reverse rotation of the core element is arrested and the thread held under sufficient tension to keep it in a firmly wound condition on the core element while the latter remains in a quiescent state.

The mechanism forming the subject matter of the present invention is particularly applicable to the unraveling of present day "non-run" fabric, wherein the interlocking of the stitches is such that the thread is more apt to become snarled at the point of unraveling than is the thread of plain knitted fabrics.

The construction and operation of the mechanism forming the subject of the present invention, and its application to and cooperation with the elements of a machine of the type noted, will be fully disclosed hereinafter, reference being had to the accompanying drawings, in which:

Figure 1 is a front elevation of a machine equipped in accordance with the principles of the present invention;

Fig. 2 is a plan view of the machine shown in Fig. 1;

Fig. 3 is a fragmentary plan view, drawn to an enlarged scale, of a single pulling and winding head of the machine shown in Fig. 2;

Fig. 4 is an enlarged transverse sectional elevation taken on the line 4—4, Fig. 1, with the elements shown in normal pulling and winding relation to the driving mechanism; and

Fig. 5 is a view similar to Fig. 4 showing the elements in the positions assumed upon excessive tension developing in the thread intermediate the core element and the fabric being unraveled.

The machine in general comprises a pair of end frames 1 and 2 respectively, one or more center frames (not shown) which are rigidly maintained in laterally spaced relation to each

other by means of longitudinally extending spacing bars 3, 3 and 4, 4 respectively.

Secured to the end frame 1, in the present instance, is a motor-supporting bracket 5 upon which is mounted an individual motor 6. The motor 6 is operatively connected, by means of a belt 7, to a pulley 8 which is secured to a transversely extending shaft 9. The shaft 9 is rotatably mounted in bearings 10, 10 carried by the end frame 1. Secured on the opposite ends of the transversely extending shaft 9 are beveled pinions 11, 11 respectively. The bevel pinions 11, 11 intermesh with beveled gears 12, 12 respectively, which are respectively secured to corresponding ends of a pair of longitudinally extending shafts 13, 13. The longitudinal shafts 13, 13 are rotatably mounted in bearings 14, 14 and 15, 15 carried by the end frames 1 and 2 respectively.

Secured to the opposite end of each of the shafts 13, 13, adjacent to the end frame 2, is a pinion 16 which intermeshes with a gear 17 rotatably mounted on the end frame 2. The gear 17 is provided with a pinion 18 which is secured thereto and intermeshes with a gear 19 which is secured to a shaft 20. The shaft 20 is rotatably mounted in a bearing 21 secured to the end frame 2. Secured to each shaft 20 is a circular cam 22 having a laterally varying cam track 23 against which bears a cam follower 24. The cam follower 24 is carried by the upper end of an arm 25 which is pivotally mounted at 26 to a bracket 27 secured to the end frame 2. The arms 25, 25 are operatively connected by a transversely extending bar 28, at the center of which is connected one end of a spring 29, the opposite end of which is secured to the end frame 2 and functions to rock the arms 25, 25 on their pivots and to hold the cam followers 24, 24 in resilient contact with the cam tracks 23, 23 of the circular cams 22, 22, whereby rotation of said cams effects rocking motion of the arms 25, 25 in unison.

Secured to each of the shafts 13, 13 in laterally spaced relation to each other longitudinally of said shafts is a series of friction wheels 30, 30, each of which is adapted to have peripheral contact with the peripheral surface of a friction pinion 31 secured to one end of a core element 32 upon which the thread of a piece of fabric to be unraveled is arranged to be wound.

In the present instance, the winding cores 32 are each in the form of a spool comprising a cylindrical body and a flange 33 at each end thereof, whereby the thread is wound on said cylindrical body intermediate the said end flanges of the core element.

Each core element or spool 32, in the present instance, is provided with either a pair of trunnions integrally secured thereto and projecting in opposite directions from the opposite ends thereof or a spindle 34 extending completely through the spool, axially thereof, and beyond the opposite ends thereof, to provide trunnions for rotatably supporting the spool with the friction pinion 31 thereof in peripheral contact with the constantly rotating drive wheel 30 secured to the shaft 13. The trunnion 35 afforded by one end of the spindle 34 is rotatably mounted in a substantially V-shaped open topped socket bearing 36 formed in one side of a bracket 37.

The bracket 37 is provided with a head 38 which is secured, by means of a clamp bolt 39 and a clamp plate 40 to a pair of the said longitudinally extending spacer bars 4, 4 which

are disposed in relatively close parallel relation to each other, as shown in Fig. 4.

The trunnion 41, afforded by the second end of the spindle 34, is rotatably mounted in a V-shaped open-mouthed bearing 42, which is formed in the side of the bracket 37 opposite that in which the open-mouthed bearing 36 for the trunnion 35 is formed. However, the bearing 42 is provided with a step 43 disposed in vertically spaced relation to the bottom 44 of the bearing 42, in which the trunnion 41 normally rests, the trunnion 41 being disposed at the end of the spool 32 at which the friction pinion 31 of the spool is located for purposes which will be hereinafter described.

The brackets 37, 37 are similar in construction, each having one of the open-mouthed bearings 36 on one side and one of the open-mouthed step bearings 42 on the opposite side, and the brackets are so arranged on the supports 4, 4 as to provide a pair of the said bearings for each of the spools supported by and between each pair of brackets.

Rotatably mounted in the outer end of each of the brackets 37 is a roller 45 upon the periphery of which is adapted to roll a longitudinally extending bar 46. Two of these bars 46 are provided, one at each side of the machine and each bar is operatively connected at one of its ends to one of the rocking arms 25, said bar being laterally guided by and between opposed faces 47 and 48 of a deep groove 49 in which the roller 45 is mounted.

Each of the bars 46 is provided with thread guides 50, 50, each of which is adapted to traverse the face of one of the spools 32, between the planes of the inner surfaces of the flanges thereof to lay the thread in superposed convolute layers upon the core element 32 during rotation of the shafts 13, 13 and the circular cams 22 by which the core elements 32, 32 are rotated and the bars 46, 46 reciprocated longitudinally, as the core elements respectively draw the threads from independent pieces of fabric as the fabric is raveled.

The fabric or fabrics to be raveled may be supported in any suitable manner and in the present instance a rack is provided above the various winding and unraveling heads, each of which includes one of the core elements 32. The rack in the present instance comprises a pair of vertically extending uprights 51, 51 which may be supported in any suitable manner from and by any convenient relatively fixed portion of the machine.

Extending between the uprights 51, 51 is a series of cross bars 52, 52 on each of which is disposed a series of clamp straps 53 which may be of a spring nature. Each series of clamps 53 is secured to a hook bar 54. Each hook bar is provided with a series of hooks 55 on which a piece of fabric X, to be unraveled, may be attached, preferably along one edge X¹ thereof with the opposite edge X² free and depending therefrom. The raveling of the fabric necessarily progresses counterclockwise of the fabric, consequently the fabric X will be hung with the edge X² thereof substantially parallel to the supporting bar 54. Obviously, an exceptionally long piece of fabric may have one edge, such as that illustrated at X¹, fastened to the hooks 55 after which the fabric may be folded and a portion thereof intermediate the edges X¹ and X² attached to the hooks, in order to suspend the

raveling edge X^2 at a desired distance above the raveling and winding heads of the machine.

The thread x of which the fabric is composed is led from the edge X^2 of the fabric, down around and under a thread guide 60 which is carried on the outer end of a tension arm 61, the opposite end of which is pivotally mounted at 62 in a bracket 63 which, in the present instance, is secured to the longitudinal spacer bars 4, 4 by the clamp bolt 39 by which the bracket 37 is secured in place.

Adjacent the outer end of the tension arm 61, within a notch 64 formed in said arm, is a resistance rod 65, to the lower end of which is permanently secured a weight 66, which is adapted to support one or more superposed and readily detachable weight plates 67, by which the amount of tension in the thread x necessary to release the spool 32 from the driving wheel 30 is accurately determined.

The thread x , after passing under the thread guide 60, passes upwardly through the thread guide 59 of the traversing bar 46 to and around the spool 32, and in order to permit lateral movement of the thread x with respect to the thread guide 60, to prevent added tension being placed on the thread by reason of the motion of the traversing bar 46, each thread guide 60 is of the elongated open type, as clearly shown in Fig. 1.

Intermediate its opposite ends, each of the tension arms 61 is provided with a shoe 68 which normally is disposed immediately adjacent to the periphery of the flange 33 at one end of the spool 32 in the plane intersecting that of the flange 33, which is disposed at the end of the spool to which the driving pinion 31 is secured.

In order to prevent the thread guide 60 from dropping under the influence of the weights 66 and 67, as a result of breakage of the thread x , the tension arm 61 is constructed in a manner illustrated in Figs. 3 and 4. Each tension arm 61 is formed of a piece of heavy gage wire bent, in the manner illustrated in Fig. 3, substantially at right angles to the body of the arm to provide a pivot portion 69 which is rotatably mounted in a lug 70 formed on the bracket 63. The arm 61 is provided with an end portion 72 extending substantially parallel to the body portion of the arm 61, as produced by bending the end of the wire at right angles to the pivot portion 69 of the arm. The end 72 of the arm 61 is arranged to bear on a horizontal extension 73 of the bracket 63 adjacent to the bearing 70 for the tension arm 61, whereby the arm 61 will be suspended in a substantially horizontal plane.

When the tension on the thread x overcomes the resistance to the lifting of the arm 61, as afforded by the weights 66 and 67, the tension in the thread x will cause the tension arm 61 to swing upwardly about its pivot, bringing the shoe 68 into contact with the periphery of the flange 33 of the spool 32. Continued raising of the arm 61, as the thread is wound on the spool 32 by rotation thereof through the medium of the wheel 30, causes the trunnion 41 of the spool 32 to be raised out of its socket bearing 44 in the bracket 37, to or beyond the level of the horizontal portion 43a of the step 43 in said bracket adjacent to said bearing, whereby the pinion 31, at the one end of the spool 32, is raised clear of and out of contact with the peripheral surface of the friction wheel 30, whereby rotation of the spool 32, in a direction

to wind the thread x thereon, is immediately arrested. The tendency of the spool 32 is then to rotate in a direction to cause unwinding of the thread x therefrom. This tendency, in the present instance, is utilized to displace the trunnion 41 from its raised position in vertical alignment with its socket bearing 44 into a laterally disposed position in vertical alignment with the horizontal portion 43a of the step 43 in the bracket 37 adjacent to the bearing 44.

Lateral displacement of the trunnion 41, as above noted, is effected by the peripheral surface of the spool flange 33 rolling on the upper surface of the brake shoe 68 carried by the tension arm 61. This rolling contact between the periphery of the flange 33 and the shoe 68 moves the trunnion 41 laterally into contact with an abutment 43b extending vertically from the horizontal portion 43a of the step 43.

Further rotation of the spool 32 in a direction which would unwind the thread x from said spool is prevented by the frictional contact between the periphery of the flange 33 and the brake shoe 68, whereby the thread is maintained under tension and keeps the said thread from becoming loose on the spool 32, said tension also maintaining the trunnion 41 on the step 43 of the bracket 37, whereby reengagement between the constantly rotating drive wheel 30 and the pinion 31 carried by the spool 32 is effectively prevented.

Normal operation of the misplaced spool may be restored, by removing the cause for the abnormal resistance to the unraveling of the thread at the point where the thread x leaves the fabric X , whereupon the tension in the thread x is slackened permitting the arm 61 to drop under the influence of the weights 66 and 67; and by manually removing the trunnion 41 from the step 43 and placing it in its bearing 44, whereby peripheral engagement between the wheel 30 and the pinion 31 is restored.

I claim:

1. A machine for reclaiming thread from knitted fabric comprising a thread pulling member, a constantly operated driving member therefor, a support for said thread pulling member, a second support for said member, and means operative when the tension on the thread exceeds a predetermined amount for causing that portion of the thread under tension to exert force on said thread pulling member to move the member from the first mentioned support to the second mentioned support.

2. A machine for reclaiming thread from knitted fabric comprising a support for a body of fabric to be unraveled, a thread pulling member, a constantly operated driving member therefor, a support for said thread pulling member, a second support for said member positioned above the first mentioned support, and means operative when the tension on the thread reaches a predetermined amount for causing that portion of the thread under tension to exert force on said thread pulling member to raise the member out of its driven engagement within the first mentioned support, said means being effective when the thread stops unraveling to raise the thread pulling member to the second mentioned support whereby this member is held permanently disengaged from its driving member.

3. A machine for reclaiming thread from knitted fabric comprising a rotary thread pull-

ing member having a peripheral driving surface, a trunnion projecting from one end of said pulling member, a bearing for said trunnion, a constantly rotating member having a peripheral 5 driving surface in contact with the peripheral driving surface of said pulling member, a support for said trunnion adjacent said bearing, and means controlled by that portion of the thread under tension to exert force for moving 10 said trunnion from said bearing to said support for effecting and maintaining disengagement of said peripheral driving surfaces when the thread becomes excessively taut.

4. A machine for reclaiming thread from 15 knitted fabric comprising a rotary thread pulling member having a peripheral driving surface, a trunnion projecting from one end of said pulling member, a bearing for said trunnion, a constantly rotating member having a peripheral 20 driving surface in contact with the peripheral driving surface of said pulling member, a support for said trunnion adjacent said bearing, means controlled by that portion of the thread under tension to exert force for moving said 25 trunnion from said bearing to said support for effecting and maintaining disengagement of said peripheral driving surfaces when the thread becomes excessively taut, said means stopping reverse rotation of said pulling element subsequent 30 to said disengagement.

5. A machine for reclaiming thread from 35 knitted fabric comprising a spool, a friction wheel on said spool, a constantly rotating friction wheel having peripheral driving engagement with the friction wheel of said spool for winding the thread on said spool, a trunnion at one end of said spool adjacent said wheels, a bearing for 40 said trunnion, a support for said trunnion adjacent said bearing, and means controlled by that portion of the thread under tension to exert force for shifting said trunnion from said bearing to said support to effect and maintain disengagement of said wheels when the thread becomes excessively taut.

45. 6. A machine for reclaiming thread from knitted fabric comprising a spool, a flange on one end of said spool, a friction wheel on said spool adjacent said flange, a constantly rotating friction wheel, a trunnion on said spool adjacent 50 the friction wheel thereon, a bearing for said trunnion normally supporting said end of said spool with said friction wheels in operative driving engagement to wind said thread on said spool, a support for said trunnion adjacent said bearing, and a lever controlled by that portion of said 55 thread under tension and arranged to engage said flange for shifting said trunnion from said bearing to said support to effect and maintain disengagement of said wheels when the thread becomes excessively taut.

7. A machine for reclaiming thread from 5 knitted fabric comprising a spool, a flange on one end of said spool, a friction wheel on said spool adjacent said flange, a constantly rotating friction wheel, a trunnion on said spool adjacent the friction wheel thereon, a bearing for said 10 trunnion normally supporting said end of said spool with said friction wheels in operative driving engagement to wind said thread on said spool, a support for said trunnion adjacent said bearing, a lever controlled by that portion of said 15 thread under tension, and a shoe on said lever arranged to have rolling contact with said flange to shift said trunnion from said bearing to said support to effect and maintain disengagement of said wheels when the thread becomes excessively taut.

8. A machine for reclaiming thread from 20 knitted fabric comprising a spool, a flange on one end of said spool, a friction wheel on said spool adjacent said flange, a constantly rotating friction wheel, a trunnion on said spool adjacent the friction wheel thereon, a bearing for said 25 trunnion normally supporting said end of said spool with said friction wheels in operative driving engagement to wind said thread on said spool, a support for said trunnion adjacent said bearing, a lever controlled by that portion of said 30 thread under tension, a shoe on said lever arranged to have rolling contact with said flange to shift said trunnion from said bearing to said support to effect and maintain disengagement of said wheels when the thread becomes excessively taut, and an abutment for arresting the 35 rolling action of the flange on the shoe and preventing reverse rotation of said spool.

9. A machine for reclaiming thread from 40 knitted fabric comprising a spool, a flange on one end of said spool, a friction wheel on said spool adjacent said flange, a constantly rotating friction wheel, a trunnion on said spool adjacent the friction wheel thereon, a bearing for said 45 trunnion normally supporting said end of said spool with said friction wheels in operative driving engagement to wind said thread on said spool, a support for said trunnion adjacent said bearing, a lever controlled by that portion of said 50 thread under tension, a shoe on said lever arranged to have rolling contact with said flange to shift said trunnion from said bearing to said support to effect and maintain disengagement of said wheels when the thread becomes excessively taut, an abutment for arresting the 55 rolling action of the flange on the shoe and preventing reverse rotation of said spool, and means carried by said lever for determining the tension of the thread necessary to effect said shifting of the spool trunnion.

HANS WESTKOTT.

60
